UNITED STATES PATENT OFFICE.

JOSEPH MOORE, JR., OF FREEPORT, ILLINOIS.

DRAWBAR CARRY IRON.

Application filed February 25, 1924. Serial No. 695,019.

To all whom it may concern:

Be it known that I, JOSEPH MOORE, Jr., a citizen of the United States, residing at Freeport, in the county of Stephenson and State of Illinois, have invented certain new and useful Improvements in a Drawbar Carry Iron, of which the following is a specification.

This invention relates to improvements in 10 stirrups or carry iron constructions for the draft gear of railway rolling stock.

The primary object of this invention is the provision of improvements in draw bar or draft gear carry iron or stirrup constructions which includes a novel carry iron construction which may be conveniently attached or detached with respect to the striking plate.

A further and important object of this invention is the provision of a relatively simple and easy operated stirrup or carry iron for the draft gear of rolling stock which includes an easily detached carry iron member normally held into locked relation with a striking plate by means of a releasable latch mechanism which may be conveniently operated without the loss of any parts.

Other objects and advantages of the improved stirrup or carry iron construction 30 will be apparent during the course of the following detailed description.

In the accompanying drawings, forming a part of this specification, and wherein similar reference characters designate corresponding parts throughout the several views.

Figure 1 is a front elevation of the improved stirrup showing the position of the same upon the beam of a car, and in assembled relation for movably supporting a draw bar.

Fig. 2 is a plan view of the details illustrated in Figure 1.

Fig. 3 is a front elevation, partly in cross section, showing cooperating details of the improved stirrup, more particularly illustrating the manner in which the latch or bolt means may be operated to permit the removal of the carry iron member with respect to the striking plate.

Figs. 4, 5 and 6 are cross sectional views taken on their respective lines in Figure 3 of the drawings.

Fig. 7 is a fragmentary perspective view of substantially a half portion of the body or striking plate, and

Fig. 8 is a perspective view of the pre-

ferred form of carry iron associated with this invention.

In the drawings, wherein for the purpose of illustration is shown but the preferred embodiment of this invention, the letter A may generally designate the improved stirrup or draft gear support which is adapted for attachment upon the end sill of a car or other piece of rolling stock C to properly support the draw bar D of suitable draft gear thereon. This stirrup or strap includes a striking plate E; carry iron F; and means G for latching of the carry iron member F with respect to the striking plate E.

The stirrup body or striking plate E is constructed of metal, and includes the attaching flanges or feet 10 and 11 adapted to overlie the under or side surface of the car sill B for attachment to the latter by means of bolts 12. The striking plate also includes the downwardly projecting arms or stationary jaws 13 and 14 which provide a slot or opening 16 therebetween within which the draw bar D and carry iron F are received. The side surfaces of the slot 16, which are in fact the facing surfaces of the arms or projections 13 and 14 are provided with the substantially L-shaped recesses 15 therein, and an end of each of said recesses 85 opens on the front surface of the jaw or arm in which the recess is formed; the recess then extending downwardly along the jaw or arm 13 providing a recess portion 15^a adapted to receive an end of the carry iron F, as will be subsequently described.

The carry iron member F is of durable metal, and of relatively simple formation providing a body portion 20 with the end extensions 21 and 22 adapted to be received in the recesses 15 and to rest in the lower socket portions 15^a of said recesses when the carry iron is in place. When so positioned the carry iron F is supported by the jaw or arm portions 13 and 14 of the striking plate E and the carry iron cannot become laterally displaced but must first be lifted in the recesses 15 in order to dislodge the same therefrom; this being due to the L-shaped formation of the recesses, and as 105 is illustrated in Figure 6 of the drawings.

Referring to the latch construction G as used in connection with the improved stirrup A, the same preferably contemplates the provision of a pair of sliding bolts 25, slideable within sockets 26 provided therefor inwardly from the ends of the carry iron mem-

ber F. These bolts or latch members 25 are of novel formation, including the bolt head 27 at one end; and the cylindrical body 28 with an annular groove 29 provided there-
 5 in adjacent the end opposite the head 27. The latch members or bolts 25 are slipped into their sockets 26 so that the heads 27 lie adjacent the outer ends of the carry iron F. A spiral compression spring 31 is em-
 10 ployed with each bolt 25, receiving the body portion 28 of the bolt therein and engaging the head 27 at one end and at its other end engaging against an annular shoulder 33 provided as a part of the carry iron socket
 15 26. The springs 31 normally act upon the latch members 25 to force the bolt heads 27 thereof outwardly from the end surfaces of the carry iron extensions 21 and 22. Suitable transverse keeper openings 35 are pro-
 20 vided through the jaws or arms 13 and 14 of the striking plate E, into which the bolt heads 27 extend to lock the carry iron into assembled relation with the arms 13 and 14 of the striking plate E, and as will be ap-
 25 parent to those skilled in the art to which this invention relates.

The normal operation of the latch device G is such that the members 25 are urged by the springs 31 into a locking relation with the striking plate. To prevent accidental displacement of the latch bolts 25 from this position, suitable retaining pins 40 are em-
 30 ployed, and may be attached by means of flexible chains 41 to the carry iron, so that they may be moved for insertion through transverse openings 44 provided through the carry iron. These retaining pins are each provided with a reduced end 45 adapted to cooperate against the end surface of the body 28 or in the annular groove 29 in order to either retain the latch member or bolt 25 in a locked relation or in an unlocked relation with respect to the parts of the stirrup A.

45 Referring to the operation of this invention, and assuming that the carry iron is detached from the striking plate, in order to assemble the carry iron in the striking plate it will be necessary to maintain the latch bolts 25 in a withdrawn position with-
 50 in their sockets 26. To permit this the latch members 25 are forced inwardly of their sockets 26 and the pins 40 are then inserted through their openings 44 until the reduced ends 45 of said pins 40 engage in the annular grooves 29, and said pins 40 will thus hold the bolts or latches 25 in the withdrawn position which is illustrated in the cross sectional view of Figure 4, for the left hand latch device. The carry iron may then be assembled conveniently and quickly into the recesses 15 into the position above defined. When the carry iron is at rest in the bottom portions 15a of the recesses 15 the socket
 55 26 will be in alignment with the transverse openings 35 through the arms 13 and 14

of the striking plate. Upon withdrawal of the pins 40 the latches or bolts 25 will then be thrown by their springs 31 into the openings 35, and the carry iron will be locked against relative movement with respect to 70 the striking plate. It will then be desirable to lock the bolts 25 against accidental movement, and this result is attained by again inserting the pins 40 until the reduced portions 45 engage the ends of the body portion 75 28 of said bolts 25, substantially in the position illustrated by the right hand latch mechanism in the cross section view of Figure 4. The carry iron and its striking plate being in assembled relation with the bolts 80 locking the former in the latter, the bolts 25 may be depressed into their sockets 26 by means of a suitable post or tool 50 which is inserted in the transverse openings 35 to act upon the bolt heads 27 to effect de- 85 pression, substantially as is illustrated in Figure 3 of the drawings. With the carry iron in place in the striking plate the same forms a support for the draw bar D, as will be readily understood by those skilled in 90 the art to which this invention relates.

From the foregoing description of this invention it is apparent that a relatively simple and easily operated type of stirrup for the support of draw bars of draft gear 95 has been provided, in which the carry iron member may be readily attached or detached with respect to the striking plate, without the necessity of unscrewing bolt nuts, and the taking out of cotter pins, as is now the case with carry iron constructions, and with which there is much waste when it is desired to disassemble the draw bar therefrom. The improved stirrup is economical, costs little for maintenance, is labor saving, easily operated, is absolutely safe in operation, and does not entail loss of parts incident to disconnection.

100 Various changes in the shape, size, and arrangement of parts may be made to the 110 form of invention herein shown and described, without departing from the spirit of the same or the scope of the claims.

I claim:

1. A device of the class described comprising a striking plate, a carrying iron, bolts slideable in the carrying iron, and means for locking the bolts into extended relation in the striking plate for locking the latter and the carrying iron together. 115

2. A device of the class described comprising a striking plate, a carrying iron, bolts, spring means normally acting on the bolts to lock the striking plate and carrying iron together, and means for holding the bolts in 120 or out of locking relation with respect to the striking plate and carrying iron.

3. In a device of the class described the combination of a striking plate having a slot extending upwardly therein, a carrying iron, 130

bolts slidable in the ends of said carrying iron, spring means in said carrying iron acting on the bolts to normally extend the same from the ends of the carrying iron, the opposite faces of said striking plate slot having sockets therein for receiving the bolts of the carrying iron for locking the latter to the striking plate.

4. A device of the class described comprising a striking plate having downwardly extending spaced arms provided with transverse aligning openings therein, a carrying iron having sockets in the ends thereof, bolts slidable in said sockets, and means for locking the bolts in extending relation from said sockets, said carrying iron when assembled to the arms of said striking plate being adapted to have the bolts thereof aligning with the transverse openings of said arms whereby when locked in extended relation they will extend into the openings of said arms for locking the carrying iron to the striking plate.

5. In a device of the class described the combination of a carrying plate having downwardly extending spaced arms pro-

vided with aligning transverse apertures therethrough, a carrying iron adapted for detachable support by the arms of said striking plate, spring operated bolts normally urged into outwardly extending relation from said carrying iron, means for locking said bolts in retracted or extended relation with respect to said carrying iron, the bolts when extended adapted to extend into the transverse apertures of the arms of said striking plate for locking the latter and the carrying iron together.

6. As an article of manufacture a carrying iron having end sockets therein, bolts slidable in said end sockets, springs normally urging the bolts outwardly of the ends of the carrying iron, and pins for locking the bolts in retracted or extended relation with respect to said carrying iron.

7. As an article of manufacture a carrying iron having sockets in the ends thereof, bolts slidable in said ends, and springs operating on said bolts to normally urge the same into extended relation at the ends of said carrying iron.

JOSEPH MOORE, Jr.
